SAFETY DEVICE FOR PUMP-GOVERNORS.

1,115,511.

Specification of Letters Patent.

Patented Nov. 3, 1914.

Application filed October 9, 1912. Serial No. 724,708.

To all whom it may concern:

Be it known that I, PHILIP L. CRITTENDEN, a citizen of the United States, residing at Edgewood, in the county of Allegheny and State of Pennsylvania, have invented new and useful Improvements in Safety Devices for Pump-Governors, of which the following is a specification.

This invention relates to pump governors for motor driven fluid compressors, and more particularly to a safety or protection device adapted to be employed in connection therewith.

It has heretofore been customary to provide some form of unloading or starting device in connection with the governor of a motor driven fluid compressor so that in starting, the motor can attain its normal speed without undue load. It occasionally happens, however, that current gives out temporarily and if the pump governor should happen to be in the cut-in position at that time, the parts will remain in said position and then when the current comes on again, the unloading device will be ineffective to prevent undue load on the motor.

The principal object of my invention is to provide means for automatically causing the pump governor to shift to the cut-out position upon failure of current, so that when current is again supplied, the parts of the starting or unloading device will be in the position to pass through the necessary cycle for preventing an undue starting torque or excessive load on the motor.

In the accompanying drawing; Figure 1 is a sectional view of an electric pump governor with my improvement applied thereto and Fig. 2 a diagrammatic view of a motor driven fluid compressor equipment showing my invention embodied therein.

In order to illustrate one form of my invention, an electric pump governor 1 of a well known type is shown comprising a switch piston 2 for actuating movable contacts 3 adapted to engage with stationary switch contacts 4 for closing the circuit which supplies current to the electric motor of the air compressor 8. A main valve mechanism comprising a valve 5 and pistons 6 and 7 controls the admission and release of fluid under pressure to and from the switch piston 2.

A low tension regulating device comprising a diaphragm 9 subject on one side to pump pressure through passage 10 controls a valve 11 adapted to govern the release of fluid under pressure from the piston 7 and a high tension regulating device comprising a diaphragm 12 subject on one side to pump pressure through the passage 13 controls a valve 14 for governing the release of fluid from piston 6. A passage 15 supplies fluid at pump pressure to valve chamber 16 and pistons 6 and 7 being loosely fitted, fluid equalizes on opposite sides of said pistons.

When the pump pressure is less than the adjusted tension of spring 17, the diaphragm 9 opens valve 11 and vents fluid from the piston 7, causing the main valve mechanism to assume the position shown in Fig. 1, in which a cavity 18 connects port 19 leading to switch piston 2 with an exhaust port 20, so that piston 2 is pressed to its inner position by spring 21, closing the switch and the pump circuit. Upon a rise in pump pressure to exceed that of spring 22, the valve 14 is opened, valve 11 having been previously closed by the rise in pump pressure acting on diaphragm 9. Fluid is thereupon vented from piston 6, while fluid under pressure has equalized around piston 7 and the main valve mechanism is shifted to its opposite position, in which passage 19 is opened to valve chamber 16, so that fluid under pressure is admitted to piston 2, thereby shifting same to its outer position, breaking the pump motor circuit.

Any type of unloading device may be employed, the form shown in the drawing being of the type adapted to gradually vary the resistance in the motor circuit in starting the motor. As shown, the starting device may comprise a casing 23 having a piston chamber 24 containing a piston 25, subject on one side to the pressure of a spring 26 and having its opposite side connected by a pipe 27 to a passage 28 leading to the seat of slide valve 5. Piston 25 is adapted to operate a contact drum 29 adapted to engage with contact fingers 30 for varying the resistance in the motor circuit.

Upon movement of the main valve mechanism to the cut-in position, as shown in Fig. 1, a restricted port 31 in the valve 5 registers with port 28, so that fluid is gradually sup-

plied from valve chamber 16 to the piston chamber 24. By this means a gradual movement of the piston 25 is effected and thereby the drum 29 is rotated to gradually cut out 5 resistance in the motor circuit.

According to my improvement, means are provided for automatically effecting the movement of the electric pump governor to its cut out position upon failure of current in the line circuit and for this purpose I preferably employ a valve 32 controlled by a magnet 33, connected across the line circuit, as shown in Fig. 2, for venting fluid from the piston 6 of the main valve mechanism of the 10 governor.

The valve 32 is normally held closed by the energization of the magnet 33, but when the current fails, the valve 32 opens and fluid is vented from piston 6 through pipe 34 to 15 exhaust port 35. By this means, if the pump governor should happen to be in its cut-in position when the current fails, the operation of the magnet controlled valve 32 automatically effects the shifting of the governor parts to 20 the cut-out position, so that when the current again comes on, the governor will be in the cut-out position and when the governor subsequently moves to cut-in position, due to a drop in pump pressure, it will be evident 25 that the unloading or starting device will be ready to operate in the usual manner to prevent an undue starting load on the pump 30 motor.

It will be understood that my improvement may be employed in connection with 35 various types of starting devices, such as the form in which an automatic valve device operates to relieve the fluid pressure on the pump piston at starting, a variable resistance adapted to be gradually cut out of the 40 motor circuit as the speed increases, or in connection with alternating current on single phase motors where various devices are employed to reduce the starting torque of 45 the motor.

Having now described my invention, what

I claim as new and desire to secure by Letters Patent, is:—

1. The combination with an electric motor driven pump for compressing fluid and a 50 governor controlled by variations in pump pressure for opening and closing the pump motor circuit, of a magnet controlled by current supplied from the source which supplies current to the pump motor circuit and a 55 valve controlled by said magnet and adapted upon failure of current to open and vent fluid from said governor to shift same to its cut-out position.

2. The combination with an electric pump 60 governor comprising an electric switch, an actuating piston therefor, and a valve mechanism operated according to variations in pump pressure for controlling the fluid pressure on said actuating piston, of an 65 electro-magnetically controlled valve operated upon failure of current for venting fluid from said valve mechanism to thereby effect the movement of said electric switch to the cut-out position.

3. The combination with an electric pump governor comprising an electric switch for controlling the pump motor circuit, an actuating piston therefor, a valve for controlling the fluid pressure on said piston, and a movable abutment operated by venting fluid from one side thereof for actuating said valve to vary the fluid pressure on said piston to thereby shift the switch to cut-out position, of a magnet normally energized by current supplied from the source which supplies current to the pump motor circuit and a valve controlled by said magnet and adapted upon failure of current to vent fluid from 70 said abutment.

In testimony whereof I have hereunto set my hand.

PHILIP L. CRYTTENDEN.
